UNITED STATES PATENT OFFICE.

DAVID L. WILLIAMS, OF BESSEMER, ALABAMA.

PIPE-FORMING PLANT.

Application filed May 19, 1920. Serial No. 382,472.

To all whom it may concern:

Be it known that I, DAVID L. WILLIAMS, a citizen of the United States, residing at Bessemer, in the county of Jefferson and State of Alabama, have invented certain new and useful Improvements in Pipe-Forming Plants, of which the following is a specification.

This invention relates to pipe forming machines, and it comprises a turntable adapted to receive moulding flasks, a sand chute arranged above said turntable, whereby a flask arranged thereon may be turned to the proper position and filled with sand, the flasks being rammed while on said turntable, a conveyor table for receiving said flasks, a shakeout hopper arranged near said conveyor, said conveyor being adapted to deliver the flasks to said hopper after the flasks have been poured, a second conveyor for returning said flasks to the turntable, and a conveyor for returning the sand from the hopper to a sand bin arranged near said chute; all as more fully hereinafter set forth and as claimed.

In the present invention, I have devised an apparatus for pipe making wherein a turntable is employed, the turntable being adapted to receive flasks for making pipes of different sizes or diameters, and is so arranged that any of the flasks may be turned to the proper position for receiving the moulding sand from a sand chute. When the necessary amount of sand has been delivered to the flask, the flow of sand from the chute may be cut off and the flask turned to another position to permit filling of a second flask. The flasks are removed from the turntable after they have been rammed by an overhead crane and carried to one of two conveyor tables. When a sufficient number of flasks have been arranged on one of the conveyor tables, the metal is poured and the flasks conveyed to a shakeout hopper arranged near the end of the table. The moulded pipe is separated from the sand, the sand being returned to a bin from which it is fed to the hopper. While one of the conveyor tables is receiving flasks which have been filled with sand, the empty flask from the other conveyor table may be returned to the turntable.

In the accompanying drawings, I have shown one embodiment of the invention. In this showing,

Figure 1 is a plan view of the apparatus.

Figure 2 is a side elevation thereof.

Figure 3 is a plan view of the turntable.

Figure 4 is a vertical sectional view of the turntable, and

Figure 5 is a transverse vertical sectional view on the line 5—5 of Figure 1.

Referring to the drawings, the turntable

comprises a base 1 which may be suitably secured to any foundation as at 2, and which is

provided with a central pin or shaft 3 upon which the rotating portions of the turntable

are mounted. As shown, a plurality of arms

4 are arranged on the upper section of the turntable, and these arms are adapted to

form supports for the moulding flasks. Each of the arms is provided with plates or

flanges 5 arranged at the sides and adapted to hold the flasks in position. A sand chute

6 is arranged immediately above the turntable. As shown in Figure 1, the chute is so

positioned that sand may be delivered to a flask arranged on one of the arms of the turntable. The chute may be provided with suit-

able cutoff mechanism (not shown) to control the flow of sand. An elevator 7 com-

municates with the upper end of the chute and delivers sand thereto. This elevator re-

ceives the sand from a sand screen 8 which

communicates with a sand bin (not shown). A guide plate 9 is arranged beneath the

screen and is adapted to deliver the sand to

the elevator.

Arranged near the turntable is a pair of conveyor tables 10 and 11. An overhead

crane 12 is adapted to convey the flasks from the turntables to the conveyor tables. As

shown, the overhead crane travels on a track

13 arranged over the two conveyor tables and

one of the arms of the turntable. Any type

of overhead conveyor may be employed and

as shown, it is provided with a trolley wheel

14 and suitable holding means 15 to grasp the flasks and hold them while they are being

carried to the conveyor tables.

A shakeout hopper 16 is arranged near each of the conveyor tables. The shakeout

hoppers are provided with a perforated top

shown as a grating 17, and a screw conveyor

18 is arranged in each of the hoppers. A

sand return pipe 19 is in communication with the hoppers through branch pipe 20, and the

sand is adapted to be returned to the sand bin through this return pipe. In the draw-

ings, I have shown the return pipe commu-

nating with only one of the hoppers, but it is apparent that an ordinary branch pipe connection may be arranged between the other hopper and the pipe 19. The sand is 5 conveyed through pipe 19 by any suitable means. In the present instance, I have disclosed the use of compressed air for returning the sand. As shown, a compressed air pipe 21 is connected to the sand return pipe, 10 air under pressure being supplied to the pipe 21 from any suitable source.

Although I have shown and described the preferred embodiment of my invention, it is to be understood that various changes in the 15 shape, size, and arrangement of parts may be resorted to without departing from the spirit of the invention or the scope of the subjoined claim.

What I claim is:

In a pipe forming plant, a molding platform comprising a base, a turntable mounted to revolve on said base, said turntable comprising a hub, and a plurality of radial arms extending therefrom, said arms being of substantially uniform width and adapted to support molding flasks, and retaining means comprising plates secured to the sides of said arms and projecting above the surface, said plates being adapted to contact with the sides of the flasks to retain them in position. 20
25

In testimony whereof I affix my signature in presence of two witnesses.

DAVID L. WILLIAMS.
